(57) **CLAIM**

The ornamental design for a lid for coffee bottle, as shown and described.

DESCRIPTION

FIG. 1 is a top, front and right side perspective view of a lid for coffee bottle showing my new design;

FIG. 2 is a bottom, rear and left side perspective view thereof;

FIG. 3 is a top, rear and left side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is an enlarged view of portion 10 in FIG. 1.

The broken lines in the drawings illustrate portions of the lid for coffee bottle which form no part of the claimed design. The dot-dash broken lines depict reference to the enlargements and show the boundary of the enlarged view and form no part of the claimed design.

1 Claim, 10 Drawing Sheets
